UNITED STATES PATENT OFFICE.

SAMUEL CHRISTOPHER McKEOWN, OF NEWARK, NEW JERSEY, ASSIGNOR TO SPLIT-DORF ELECTRICAL COMPANY, OF NEWARK, NEW JERSEY, A CORPORATION OF NEW JERSEY.

ELECTRIC-CIRCUIT-CONTROLLING DEVICE.

1,368,517.

Specification of Letters Patent. Patented Feb. 15, 1921.

Application filed July 25, 1917. Serial No. 182,693.

To all whom it may concern:

Be it known that I, SAMUEL C. McKEOWN, a citizen of the United States, residing at #98 Warren street, Newark, in the county 5 of Essex and State of New Jersey, have invented certain new and useful Improvements in Electric-Circuit-Controlling Devices, of which the following is a specification, reference being had to the accompanying drawing.

The invention relates to new and useful improvements in electric controlling devices and more particularly to a device for controlling a battery current for producing 15 sparks for ignition purposes.

It is customary in the art to provide battery ignition which includes a primary and secondary coil, in the primary circuit of which is a make and break device for interrupting the primary circuit. This make and break device consists of contacts which are closed for establishing the current and separated for interrupting the flow of the current through the circuit.

In a device of this character, if the engine should stop with the controlling cam positioned so as to leave the contacts closed, then there would be a constant drain on the battery.

The present invention is directed to means operating automatically to separate the contacts which normally make and break the circuit for ignition purposes when the actuating mechanism therefor stops.

In the drawings:

Figure 1 shows more or less diagrammatically a circuit controlling device embodying my improvements;

Fig. 2 is a view in part similar to Fig. 1 showing a modified form of the invention;

Fig. 3 is a view in part similar to Fig. 2 but showing the actuating shaft in motion and the contacts as closed;

Fig. 4 is a side elevation of Fig. 1, some 45 of the parts being shown in section. A similar construction holds for Figs. 2 and 3.

The invention consists broadly in means for preventing the contacts which normally operate to make and break the battery circuit from closing when the actuating mechanism stops with the actuating device in the

normal position for closing the contacts. This is accomplished by providing a drum rotating with the actuating shaft and a brake band which makes contact with the drum, which brake band is shifted through a limited distance by the rotation of the drum. The tension of the brake band on the drum may be varied by suitable means. A suitable spring limits the movement of 60 the brake band and when the actuating mechanism stops this spring shifts the brake band in a direction normally opposed to its direction of rotation which results in separating the contacts, if the actuating mechanism should stop, in position to normally 65 close the contacts.

Referring more in detail to the drawings, 1 denotes a rotatable drum which rotates with the actuating shaft, indicating at 2. 70 The actuating shaft is driven in proper timing with the engine shaft when the device is used for furnishing ignition current. Extending around the rotatable drum is a 75 brake band 3. This brake band is resiliently held in place by a bolt 4, carrying a spring 5. The bolt 4 is fixed to one end of the band and extends freely through the other end thereof. A spring bears against the free end of the band at one end and against a washer 80 6 at the other end. A threaded nut 7 screwed on to the end of the bolt serves as a means for regulating the tension of the spring 5. The brake band is provided with a suitable felt lining indicated at 8. A 85 bumper spring 10 is placed between the end of the brake band and an abutment 11 fixed to the frame of the machine. This bumper spring opposes the rotation of the brake band 3. When the drum ceases to revolve 90 then this bumper spring 10 moves the brake band a short distance in a counter-clockwise direction.

Current for ignition is supplied from the battery B. The battery current is controlled 95 by an interrupter consisting of a fixed contact 12 and a movable contact 13. The fixed contact 12 is connected to ground through a suitable line 14. The movable contact is connected through the line 15 to the battery. 100 The movable contact is carried by a spring arm 16 fixed to a bracket 17. Said movable

arm is actuated by a lever 18 which is pivoted at 19 to the frame 37 of the machine. Mounted on the shaft 2 is a controlling cam 20 which engages the lever for oscillating the same. A spring 21 having one end connected to a pin 36 which is fastened to some stationary part of the device as 37, normally holds the lever in engagement with the cam. The free end of the brake band extends upwardly and is provided with a projection of insulating material indicated at 22. This projection lies directly in rear of the movable member 16.

The other terminal of the battery B is connected through a line 23 and switch 34 with a primary coil 24. A secondary coil 25 connects with the movable distributor 26 which is rotated so as to engage the contacts 27, 28, 29 and 30, in succession.

20 The operation of my device, as above described, is as follows:—

When the shaft 2 is actuated, the cam 20 will cause the lever 18 to vibrate. The rotation of this shaft also rotates the drum. 25 The brake band frictionally engaging the drum will turn with the drum in a clockwise direction to a limited extent, compressing the buffer spring 10. This movement of the brake band brings the projection 22 into contact with the movable arm 16 and closes the contacts, provided the actuating lever is in position to permit the contacts to be closed. A stop pin 33 which is to be understood to be mounted on a stationary part 37 of the device, limits the forward movement of the lever 18. Then as the cam rotates and the lever is oscillated a movement of the upper end of the lever to the left will cause the contacts to be separated, shifting 30 the brake band with the movable member carrying the movable contact. As soon however, as the shaft 2 stops in its rotation, then the buffer spring 10 will shift the drum and the brake band so as to separate the contacts regardless of whether the lever 18 stops in position for closing the contacts or not. In other words, the buffer spring 10 always insures that the contacts will be open when the engine stops and this prevents any possible 35 drain on the battery. If, however, the engine shaft is started then the contacts are automatically returned to operative position relative to each other so that the actuating mechanism will make and break the contacts in proper timing for producing ignition.

50 The device shown in Fig. 2 is similar to that shown in Fig. 1, except as to the manner of controlling the contacts.

The shaft 2 carries a drum 1 and an actuating cam 20 which operates upon the actuating lever 18. Encircling the drum is a brake band 3 having a felt lining. A bolt 4 carried by one end of the brake band extends through the other end thereof and a spring 5 determines the tension on the brake

band, in the manner above described. A buffer spring 10 limits the movement of the brake band through the rotation of the drum in a clockwise direction and rotates the brake band in the opposite direction when 70 the actuating shaft stops. Current is supplied from a battery B and this is controlled by an interrupter consisting of a normally stationary contact 12 and a movable contact 13.

75 The movable contact in this embodiment of the invention is carried directly by the actuating device 18. The normally stationary contact is mounted on a lever 26 which is pivoted to a bracket 27 that is mounted 80 on a fixed part 37 of the device but insulated therefrom. A spring 28 has one end fastened to the lever 26 by any suitable means, such as a screw 35 and the other end fixed to an abutment 29. The lever 26 85 is rigidly connected to an arm 30. The brake band is provided with a raised portion or projection 31, which is adapted to engage the rounded end of the arm 30. A spring 21 having one end connected to a 90 pin 36 which is fastened to some stationary part 37 of the device holds the actuating lever 18 in contact with its actuating cam. As the shaft 2 rotates it will vibrate or oscillate the lever 18. A stop pin 32 which 95 is to be understood to be mounted on a stationary part 37 of the device limits the forward movement of the lever 18 and a stop pin 33 also mounted on the stationary part 37 of the device limits the movement of the 100 lever 26. When the parts are in the position shown in Fig. 2, the shaft is idle and the buffer spring has turned the band and drum so that the projection or raised part 31 is ineffective to raise the arm 30. When 105 the part is in the above position the normally stationary contact is held in such position that the movable contact will not engage the same no matter what may be the position of the actuating cam 20. As soon 110 as the main shaft begins its rotation the raised portion or projection 31 will engage the end of the arm 30, forcing it outwardly as shown in Fig. 3, and this will shift the normally stationary contact to a position 115 so that the movable contact will engage the same.

115 It will be apparent from the above description that I have provided broadly means for interrupting the battery circuit 120 for producing ignition current which includes contacts which can be opened and closed and also means which prevents the contacts from being left closed by the actuating mechanism provided the shaft stops 125 with the actuating lever in position for normally closing the contacts and, therefore, under no condition can the contacts be left closed and the battery be short circuited through the engine when it is idle.

It is obvious that minor changes in the details of construction and arrangement of parts, may be made without departing from the spirit of the invention, as set forth in 5 the appended claims.

Having thus described my invention, what I claim as new and desire to secure by Letters Patent, is,—

1. The combination with an electric circuit, of a pair of make and break contacts for interrupting said circuit, actuating means for said contacts, setting means for said contacts, means movable with said actuating means for operating said setting means so the contacts can be actuated to interrupt the said circuit, said setting means acting to open said contacts when the said means movable with the actuating means is stopped.
2. The combination with a source of direct current, an electric circuit including the primary of an induction coil, interrupter members in said circuit carrying a pair of contacts normally out of operative range, an operating cam, a drum movable with said cam, a brake band operated by said drum and adapted to bring said contacts into operative range whereby said cam may oper-

ate one of the interrupter members to open and close said circuit. 30

3. The combination with an electric circuit, of a pair of make and break contacts for interrupting said circuit, actuating means for said contacts, frictional means for controlling one of said contacts and 35 adapted to maintain said contacts separated when the actuating means stops.

4. The combination with an electric circuit, of a pair of make and break contacts for interrupting the circuit, one of said 40 contacts being normally stationary and the other being movable, an actuating means for said movable contact, a drum movable with said actuating means, frictionally operated devices controlled by the drum for 45 moving the contacts into normal range of action and a spring for shifting said frictional means to separate the contacts when the actuating means stops.

In testimony whereof I hereunto affix my 50 signature in the presence of two witnesses.

SAMUEL CHRISTOPHER McKEOWN.
